CLOSURE AND MOUNTING CAP FOR
HOLLOW POSTS

Henry A. Sollmann, Cincinnati, Ohio

Application April 16, 1948, Serial No. 21,335

2 Claims. (Cl. 248—353)

1

This invention relates to a closure and mounting cap for hollow posts and more particularly relates to a cap which incorporates means for attaching hooks or fasteners or the like to a hollow tube or post for use in attaching lines, pulleys, or other fixtures to an upper end of a post.

An object of this invention is to provide a cap for a hollow post which forms a closure for the post and also incorporates means for attaching a hook or the like to the post.

A further object of this invention is to provide a cap of this class which can be formed in a simple, inexpensive manner, as by casting.

A further object of this invention is to provide means for attaching a hook or fastener to a post without need for auxiliary or transverse bores, tapping, or other machining operations.

A further object of this invention is to provide means for attaching a hook to a post, which hook may be of simple construction and easy fabrication.

The above mentioned and other objects may be attained by the means described herein and disclosed in the accompanying drawing, in which:

Figure 1 is a perspective view of a hollow post and cap constructed in accordance with this invention, the post and cap being shown in assembled relation with a plurality of hook fasteners.

Figure 2 is a perspective view of the cap shown in Figure 1.

Figure 3 is a sectional view along the line 3—3 in Figure 2.

Figure 4 is a side elevational view, partly broken away and in section, showing another cap constructed in accordance with this invention.

Figure 5 is a side elevational view of one of the hook fasteners shown in Figure 1.

Figure 6 is a vertical sectional view showing another post and cap constructed in accordance with this invention.

Figure 7 is a side elevational view of a fastener having a threaded end.

Referring now to the drawings and to Figure 1, a hollow post, which may be made of metal pipe, is indicated at 9. The post 9 has a central bore 10 and may be stepped in a socket 12 in ground 13. The post 9, shown in Figure 1, is intended for use to support a clothes line. A series of hooks or anchors 14 may be attached to the upper end of the post 9 by a plug 16 having a portion which fits into the upper end of the bore 10.

Details of construction of the plug 16 are shown in Figures 2 and 3. The plug 16 has a

roughly mushroom shaped cap 17 and a stem 18. The upper portion or cap 17 may be of larger diameter than the hollow post 9 to form a cover over the post, while the stem 18 may be of smaller diameter to fit within the bore 10. The stem 18 may taper slightly being of greater thickness adjacent the upper portion 17 and being narrower at a lower end 19 for convenience in inserting the stem 18 within the bore 10 and in order to permit the stem 18 to be driven into the upper end of the post 9 to be held therein. As shown in Figure 2, edges of the lower end 19 may be beveled, as at 20, similarly for ease in inserting the stem 18 within the bore 10.

As shown in Figure 5, each of the hooks or anchors 14 includes a rounded hook portion 21 and a side arm 22. The arm 22 and the hook portion 21 may be connected by an arm 23 which meets the arm 22 at an acute angle 24. Each hook or anchor 14 may be fabricated from heavy wire bent to the shape shown in Figure 5. No machining or difficult fabrication operations are required in their manufacture.

The plug 16, as shown in Figures 2 and 3, is provided with lengthwise slots 26 in the stem 18 and with connecting substantially radial slots 27 in the under side of cap 17. The slots 26 and 27 are adapted to receive the arms 22 and 23 of the hooks 14. The arm 22 of a hook 14 may fit into a lengthwise slot 26, and an arm 23 may fit into a radial slot 27 so that the hook 21 may extend outwardly from the cap 17. Between the slots 26 the stem may extend outwardly forming longitudinal ribs 28. The ribs 28 fit about the arms 22, and the stem 18 may have the approximate diameter of the bore 10 between the slots 26. As will be apparent, the cap 17 may be equipped with a single pair of slots 26 and 27 or, as shown, a plurality of pairs of slots to receive a plurality of hooks 14.

The plug 16 and the hooks 14 may be attached to the post 10 (Figure 1) by assembling the plug 16 and the hooks 14 and then driving stem 18 into the bore 10. The hooks may be of the same diameter as the slots 26 and 27 or may be of slightly greater diameter than the slots so that the hooks can be held firmly against the inner wall of the bore 10 when the stem 18 is driven into the bore 10.

In Figure 4 is shown a similar plug 116 which has a rounded upper portion or cap 117, a threaded stem 118, and slots 126 and 127 for receiving arms 22 and 23, respectively, of hooks 14. As will be apparent, the stem 118 may be screwed into a bore of a post (not shown) having

a threaded upper portion to hold the post and plug 116 in assembled relation with hooks.

The plugs 16 and 116 shown in Figures 1-4 inclusive are constructed to receive the hooks 14 in which the arms 22 and 23 meet at an acute angle 24. In Figure 6 is shown a plug 216 having radial slots 227 and vertical slots 226 which meet at a right angle. Fasteners 214 and 314 are held in an upper end of a hollow post 209 by the plug 216. As shown, the fastener 214 may have a side arm 222 and an arm 223 of a hook portion 221 which meet at a right angle 224.

Attachments having other configurations than that of a hook may be attached to the upper portion of a post in a similar manner. As shown in Figure 6, the fastener 314 may be equipped with an outwardly extending eye 29. The eye 29 may be used for attaching relatively permanent installations to the post. For example, a flag or a flag pole pulley may be attached to the post 209 for use thereof to support a flag.

In Figure 7 is shown a further type of fastener 414 which may be attached to a post by a cap constructed in accordance with this invention. The fastener 414 includes a side arm 422 and an arm 423 which meet at an acute angle 424 and which may be attached to a hollow post in the same manner as the other fasteners. The arm 422 may fit in the slot 26 so that the arm 423 extends outwardly from the cap 16. A free end 31 of the arm 423 may be threaded, as shown, for connection to appropriate fittings which may be supported by the post.

As will be apparent, the closure and mounting plugs of this invention permit a hook, fastener, or other fitting to be attached to the top of a hollow post without need for transverse bores, bolts, and the like which have heretofore been required. The plug 16, for example, can be formed without machining in a simple casting operation, while the hooks 14 can be formed by bending heavy wire. No dies of a complex structure are required as would be the case if the plug, post, and hooks were formed as a single, integral casting.

When a plug, post, and fasteners are mounted in assembled relation, the plug can hold the fasteners firmly without need for special connections. The slots 26 of the plug 16 can hold side arms 22 of hooks against the bore 10, while the slots 27 can hold the angled portions 24 and the arms 23 against the top of the post 9 so that the hooks 14 are restrained positively against up and down shifting and against rotation under a load on the hook portion 21.

A permanent and effective closure of the up-

per end of the hollow post is formed by the same member or plug which holds the fasteners in place. Various modifications in construction will be apparent, and the invention is not intended to be limited by the foregoing detailed description or by the drawing but only as set out in the appended claims.

What is claimed is:

1. In combination, a hollow metal post having an open top and a plug and anchor adapted to be frictionally held in the open top of said post, said plug having a tapered stem extending into the open top of the post and a cap overlying and closing same, said stem having arcuate grooves in its surface extending from the under side of said cap towards the lower end of the stem, said anchor having a cylindrical portion adapted to be received in said stem groove and another portion disposed under said cap and extending outwardly over the top of said post, said anchor and stem having a friction grip with the inside surface of said post when the stem is driven into the open end thereof.

2. A plug and anchor adapted to be driven into the open top of a hollow post and be held by friction therein, said plug comprising a stem and a cap, the cap being larger than the open top of the post and the stem being tapered from a point adjacent the base of the cap towards the end thereof and provided with an arcuate groove extending lengthwise thereof, the underside of said cap being provided with a groove communicating with and extending laterally from the groove in said stem, said anchor having a cylindrical portion substantially circular in section and of a diameter greater than the depth of said groove, and another portion adjacent the underside of said cap and extending laterally therefrom, the laterally and outwardly extending portion of said anchor registering with the groove in the underside of said cap.
